UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING DEVICE.

No. 857,039.

Specification of Letters Patent.

Patented June 18, 1907.

Application filed April 9, 1906. Serial No. 316,000.

To all whom it may concern:

Be it known that I, JOSEPH S. DUNCAN, a citizen of the United States, residing at Chicago, in the county of Cook and State of Illinois, have invented new and useful Improvements in Printing Devices, of which the following is a specification.

The object of this invention is to facilitate the insertion and removal of a type holder and a card in the frame of a printing device and also provide for locking the type holder and card in place.

In the accompanying drawings illustrating the invention Figure 1 is a front view of the printing device. Fig. 2 is a back view. Fig. 3 is a sectional view on the line 3—3 of Fig. 1.

Referring to the drawings 5 designates the frame which is provided with spacing flanges 6 at its ends and has a bead 7 at its top and a flange 8 at its bottom. The spacing flanges at each end of the frame are preferably formed with a back 9, a top 10 and a bottom lip 11 (Fig. 3). The card 12 is held in place on the frame beneath the bead 7 at the top of the frame, the lip 13 which engages one end of the card the lip 13' which engages the lower edge of the card, and the lip 14'. The stop 14 prevents the card slipping out from beneath the bead and lips and the lip 14' is located just below said stop to engage the lower right hand corner of the card and prevent the card from accidentally rising and slipping over the stop.

The type holder 15 is provided with a plurality of type grooves 16 to receive the type 17. In the drawings I have shown a holder provided with four type grooves and lines of type in three of said grooves. It is customary to provide printing devices adapted for each particular purpose and when three lines of type are desired a holder having three grooves and a frame to accommodate a holder of this capacity is provided, but it is not necessary that every groove of the holder should be supplied with a line of type. The type holder is held in place between the over-hanging lips 18 at the top of the holder and the inwardly bent flange 19 at the bottom of the holder, and it is prevented from sliding end- 45 wise by the stop 20 at one end and the lock 21 at the other end. This lock consists of a tongue 21' formed by stamping out metal from the frame (Fig. 2) and at the end of this tongue there is an upstanding lip 22 which

forms a stop to prevent endwise movement of the type holder and a handle lip 23 projecting forwardly but slightly offset to raise it above the plane of the front face of the frame. After the type holder is slid into place on the frame the spring tongue 21' carries the locking lip 20 up to prevent endwise movement of the holder and thus the holder is confined in the guiding grooves formed by the over-hanging lips 18 and the inwardly-bent flange 19 by the end stops 20, 22.

These printing devices are very largely used for printing addresses and are designed to be stored in accordance with a regular card index system. An impression of the address formed by the type in the holder is made on the card so that it can be easily read and the card may be spaced and lined in any suitable manner to receive any other desired information. To enable the device to stand in upright position in the tray or box in which they are stored the ends 19' of the flange 19 are preferably bent to a substantially horizontal position to form feet upon which and the lower ends of the guide flanges 6 the printing device will stand in upright position. The card is inserted in the frame by first entering its left hand end beneath the bead 7 and the lip 14' at the right hand end of the frame and then pushing the card into place until the right hand end has passed the stop 14. The lip 14' in conjunction with the bead 7 will hold the right hand end of the card close to the frame and prevent it from rising over the stop 14. The type holder is provided with a rib 24 at its upper edge 90 which slides under the lips 18 and the wall 25 at the lower edge of the type holder is bent inward slightly so that the flange 19 will engage therewith and hold the lower edge of the holder tightly against the frame. The locking lip 22 projects upward above the tongue and when the type holder is arranged in place in the frame it is first laid upon the locking device and then slid forward to the left beneath the lips 18 and flange 19 until the right hand end of the holder has passed the lip which is thereupon carried up by the tongue to engage the right hand end of the type holder.

The device is simple in construction and the construction and arrangement is such that both the card and the type holder can be readily inserted in or removed from the

frame. This greatly simplifies the use of devices of this character and thereby promotes their sale.

What I claim and desire to secure by Letters Patent is:

1. A printing device of the character described comprising a frame, means for removably holding a card in place on the frame, said means comprising a stop at one end of the frame to engage one end of the card, and a lip on the frame beneath said stop to overlap the corner of the card and hold the card in engagement with said stop.

2. A printing device of the character described comprising a frame and means for holding a card in place on the frame, said means consisting of a bead at the top of the frame to engage the upper edge of the card, a lip on the frame to engage the bottom of the card between its ends, a lip at one end of the frame to engage one end of the card, a stop at the other end of the frame against which the adjacent end of the card abuts, and a lip on the frame beneath said stop to overlap the lower corner of the card at the end adjacent to said stop and hold the card in engagement with said stop.

3. A printing device of the character described comprising a frame, means on said

frame for holding a type holder, and a locking device on the frame comprising a spring tongue, there being an upstanding lip and an offset handle lip on said tongue.

4. A printing device of the character described comprising a frame, and means on said frame for holding a type holder thereon, said means comprising an inwardly bent upstanding flange to engage the lower edge of the holder, the ends of said flange being bent to form feet for the holder.

5. A printing device of the character described comprising a frame, means on said frame for holding a type holder, said means comprising an over-hanging lip to engage the upper edge of the holder, an inwardly bent flange to engage the lower edge of the holder, the ends of said flange being bent to form feet for the holder, a fixed stop to be engaged by one edge of the holder, and a locking device to engage the other end of the holder, said locking device comprising a spring tongue, an upstanding locking lip, and an offset handle lip.
